UNITED STATES PATENT OFFICE.

ERVIN J. RUST, OF CLEVELAND, OHIO, ASSIGNOR OF ONE-HALF TO S. T. RINKER, OF CLEVELAND, OHIO.

DESIGN FOR A HAIR-CLIPPER.

59,434.

Specification for Design.

Patented Oct. 18, 1921.

Application filed June 1, 1921. Serial No. 474,274. Term of patent 14 years.

To all whom it may concern:

Be it known that I, ERVIN J. RUST, a citizen of the United States, residing at Cleveland, in the county of Cuyahoga and State of Ohio, have invented a new, original, and ornamental Design for a Hair-Clipper, of which the following is a specification, reference being had to the accompanying drawing, forming part thereof.

I claim:

The ornamental design for a hair clipper as shown.

ERVIN J. RUST.
